UNITED STATES PATENT OFFICE.

MILAN HRNICH, OF CONEMAUGH, PENNSYLVANIA.

RAILWAY-TIE.

1,177,413.

Specification of Letters Patent. Patented Mar. 28, 1916.

Application filed January 6, 1916. Serial No. 70,656.

To all whom it may concern:

Be it known that I, MILAN HRNICH, a subject of the Emperor of Austria-Hungary, residing at Conemaugh, in the county of Cambria and State of Pennsylvania, have invented certain new and useful Improvements in Railway-Ties; and I do declare the following to be a full, clear, and exact description of the invention, such as will enable others skilled in the art to which it appertains to make and use the same.

This invention relates to improvements in railway ties, and has for its principal object to provide a simply constructed tie which can be easily and quickly laid without the use of skilled labor.

A still further object is to provide a tie which will be practically indestructible.

With the above and minor objects in view, my invention resides in the novel features of construction, combination and arrangement of parts which will hereinafter be more particularly described and claimed.

In the accompanying drawing: Figure 1 represents a top plan view of one of my improved ties showing the rail clamps in operative position; Fig. 2 is a central vertical longitudinal section through one of the ties and the clamps; Figs. 3 and 4 are detail transverse sections taken on the lines 3—3 and 4—4 of Fig. 1; and Fig. 5 is a perspective view of one of the rail supporting blocks.

In its preferred form, my invention comprises broadly a pair of rail supporting blocks 1 which are spaced apart and connected by their adjacent ends by the channel or U-shaped connecting plate 2. Each of these blocks 1 is substantially rectangular in plan view and square in cross section, and receives one or more rails on its upper face, said blocks being arranged in longitudinal alinement as shown. The inner or adjacent end of each of the blocks is recessed on its bottom as shown at 3 to receive the bottom 4 of the connecting plate 2, said recesses being of a depth substantially equal to the thickness of the connecting plate, while the sides of said adjacent ends are recessed as shown at 5 to receive the ends of the upright portions 6 of the connecting plates. As shown in Fig. 2, these upright portions of the connecting plate extend but slightly more than half the height of the rail supporting blocks, and therefore the recesses 5 formed in said blocks, as shown in Fig. 5,

do not extend upwardly farther than a point slightly above the center thereof. By this construction, inasmuch as the widths of the blocks 1 and the connecting plate are the same, the outer sides of said connecting plate and the blocks will be flush as shown in Fig. 1, as are also the bottoms of said blocks and the plate, as shown in Fig. 2.

The recesses 5 have transversely extending openings 7 communicating therewith which are alined with the apertures 8 formed in the upright portions 6 of the connecting plate adjacent the ends thereof. These alined openings and apertures receive the pins or other fastening elements 9 which are held in place by the cotter pins 10, this particular arrangement being provided because of the greater ease with which the parts can be assembled than if bolts and nuts were used. When once the parts heretofore described have been secured in cooperative relation, a very substantial tie will be produced, and if all parts thereof are constructed of metal, it will last an extremely long time, obviously a much greater length of time than the ordinary wooden tie. The rail supporting blocks 1 may also be very readily formed from cement and which will also provide a very long lasting and strong structure.

The top of each of the rail supporting blocks 1 is provided with a longitudinally extending substantially rectangular recess 11 in which the rail clamps C are disposed in order to hold the rails R in position on the tie. I preferably provide two forms of clamps C, an outer clamp and an inner clamp, the former being considerably stronger than the latter to hold the rails against spreading. Each outer clamp comprises a rail bracing head 12 which is substantially the width of the blocks 1 and overlies the same as is shown in Fig. 1. The heads 12 are provided with seats 13 to receive the heads of the rails R and with the grooves 14 for the reception of the outer base flanges thereof. Each head 12 also has a substantially rectangular tongue 15 depending therefrom into one of the recesses 11, said tongue being substantially the width thereof, as shown in Fig. 3.

The inner clamps are preferably merely rectangular members 16 substantially the width of the grooves 11, and are provided with notches 17 to receive the inner base flanges of the rails. As shown, these inner

clamps extend only a short distance above the tops of the supporting blocks 1 and contact with but very small portions of the rails, but it is obvious that the outer rail clamps could be very easily used as inner clamps if it were desired to more securely hold the rails. In some cases it becomes necessary to support a guard rail R' on either one or both of the blocks 1, in which case an additional rail clamp 18 is provided. This clamp 18 is substantially similar to the clamps 16 with the exception that both sides thereof are provided with grooves 17' for the reception of the adjacent base flanges of the rails R and R'.

In order to secure the rail clamps against movement in the recesses 11 and hold the rails in operative position on the blocks 1, I provide the locking bolts 19 and 20 which are threaded in openings 21 in the ends, both inner and outer, of the rail supporting blocks 1. As shown these locking bolts extend into the recesses 11 and contact with the rail clamps disposed therein, the bolts 19 resting in seats in the tongues 15 of the outer rail clamps, while the bolts 20 abut the inner clamps 16. In use, the rails are disposed on the blocks the proper distance apart and the clamping members moved into contact therewith, and when this has been done, the locking bolts 19 and 20 are tightened until the rails are securely held between their respective clamps. It is obvious that an adjustment of this character can be made very quickly, and at any time.

After the bolts 19 and 20 have been tightened to secure the rails and the blocks

against longitudinal shifting on the tie, the set screws 22 which are disposed in threaded openings 23 in the sides of the blocks 1, are tightened, thus preventing any tendency on the part of the blocks or the rails to move upwardly with respect to said tie.

From the foregoing description taken in connection with the accompanying drawing, it will be readily evident that I have invented an extremely simple yet very efficient tie which is provided with means for readily adjusting and securely holding the rails thereon.

50 I claim as my invention:

A tie comprising a pair of rectangular rail supporting blocks placed in spaced apart longitudinal alignment, a channel-shaped connecting plate of a width corresponding to the width of said blocks and underlying and receiving the adjacent ends thereof in said channel, said adjacent ends being recessed on their sides and bottom for the reception of the ends of said plate and provided with transversely extending openings, the upright portions of said plate having apertures alining with said openings, connecting elements passing through said alined apertures and openings, and means 55 on said blocks for holding the rails thereon.

60 In testimony whereof I have hereunto set my hand in presence of two subscribing witnesses:

MILAN HRNICH.
